FIG. 1

FIG. 2

FIG. 3

FIG. 4

FIG. 5

FIG. 6

FIG. 7

FIG. 8

FIG. 9

FIG. 1 is a front elevational view of a dust collector showing my new design;

FIG. 2 is a side elevational view taken from the right of FIG. 1;

FIG. 3 is a rear elevational view of FIG. 1;

FIG. 4 is a top plan view of FIG. 1;

FIG. 5 is a bottom plan view of FIG. 1;

FIG. 6 is a side elevational view of a second embodiment of the design of FIG. 1, the front elevational view being identical to FIG. 1;

FIG. 7 is a rear elevational view of FIG. 6;

FIG. 8 is a top plan view of FIG. 6;

FIG. 9 is a bottom plan view of FIG. 6.

The electric cord in FIGS. 2 and 6 is shown broken away to indicate indeterminate length; said cord is omitted from all other views for convenience of illustration.

In each embodiment both side elevational views are

the same except for the electric box shown; the front elevational views of the two embodiments are the same.

I claim:

The ornamental design for a dust collector, substantially as shown and described.
